CLAIM

The ornamental design for a wheel for a building toy as shown and described.

DESCRIPTION

1.1 is a perspective view of a wheel for a building toy showing our new design.

1.2 : Front

1.3 : Back

1.4 : Top

1.5 : Bottom

1.6 : Right

1.7 : Left

1.1 is a perspective view of a toy wheel showing our new design; 1.2 is a front view thereof; 1.3 is a back view thereof; 1.4 is a top view thereof; 1.5 is a bottom view thereof; 1.6 is a right view thereof; 1.7 is a left view thereof; the line shading in reproductions 1.1-1.7 is a drawing convention to represent contours, it does not illustrate any surface ornamentation and/or decoration.

1 Claim, 7 Drawing Sheets
